UNITED STATES PATENT OFFICE

EDWARD W. HYDE, JR., OF PHILADELPHIA, PENNSYLVANIA; CATHERINE E. HYDE EXECUTRIX OF SAID EDWARD W. HYDE, JR., DECEASED

STRUCTURAL HEAD FOR REINFORCED CONCRETE CONSTRUCTION

Application filed February 13, 1929. Serial No. 339,722.

This invention relates to certain new and useful improvements in structural heads for reenforced concrete construction, the object being to provide a head of such a size that it extends outwardly a sufficient distance into the concrete slab where the slab is of itself strong enough in shear and flexure to resist the stresses that come upon it.

Another object of my invention is to provide a structural head adapted to be embedded in the upper end of a column and the adjacent portion of the slabs whereby the reinforcing rods of the column are tied to the reinforcing rods of the floor slabs so as to relieve the slabs from the heavy shearing and flexural stresses that occur close to the column whereby these stresses will be effectively resisted.

Another object of my invention is to provide a head having a lateral shelf extending outwardly from the edge thereof into the adjacent slabs so that the concrete just outside of the head represented by the distance around the shelf angle, multiplied by the vertical distance from the top of the outstanding leg of the shelf angle to the top of the slab in square inches of area constitutes the effective area to resist the shear and the lower portion of the slab just outside the shelf angle and above and below the side of the same together with the lower or horizontal leg of the angle will resist compression in its maximum amount in the slab, whereby I am able to produce a condition of strength similar to that which would be produced by a flaring concrete head or capital below the slab at the junction of the column with the slab.

Another object of my invention is to provide a structural head in which the reinforcing elements of the slabs are more effectively tied to the column in connection with means whereby the slabs are interlocked with the heads beyond the column so that a construction is produced which will withstand the stresses to which it is subjected.

A further object of my invention is to provide a structural head which is capable of being used on center of side columns, around 50 elevator shafts, air shafts or chutes and one

which is so constructed that the reinforcing rods of the slabs and columns are indirectly tied together in connection with a construction whereby the concrete of the slabs and columns are interlocked for giving an additional strength to withstand the stresses to which they are subjected.

A still further object of my invention is to provide a structural head which is exceedingly simple and cheap in construction and one which can be readily placed in position and when in position will have an interlocking connection with the reinforcing rods of the slabs and column and with the material from which the slabs and column are formed.

Other and further objects and advantages of the invention will be hereinafter set forth and the novel features thereof defined by the appended claims.

In the drawings,

Figure 1 is a top plan view of one form of structural head;

Figure 2 is a vertical sectional view of a column showing the head embedded therein and also embedded in the slabs;

Figure 3 is a vertical sectional view similar to Figure 2, of one portion of the head showing the reinforcing rods of the slabs passing through the angle and under the head;

Figure 4 is a top plan view of a structural head used on a side column;

Figure 5 is a vertical sectional view of a side column showing the head embedded therein and also in the slab;

Figure 6 is a top plan view of a structural head used on a corner column;

Figure 7 is a top plan view of a hexagonal structural head;

Figure 8 is a vertical transverse sectional view of Figure 7;

Figure 9 is a top plan view of a circular structural head;

Figure 10 is a top plan view of a structural head used on a column at the corner of an elevator or like shaft;

Figure 11 is a vertical sectional view of Figure 10;

Figure 12 is a sectional view taken on the line 12—12, Figure 10;

Figure 13 is a top plan view of a rectan-

gular structural head showing a rectangular piece cut out so that provision is made for a vent shaft or the like;

Figure 14 is a sectional view taken on the line 14—14, Figure 13;

Figure 15 is a top plan view of a structural head built of a series of angle irons, H and I beams;

Figure 16 is a vertical sectional view taken through the column and slab;

Figure 17 is a plan of a structural head made up of a series of angle irons and beams to be used on a side column;

Figure 18 is a top plan view showing a structural head made up of a single casting;

Figure 19 is a vertical sectional view through a column and slabs showing the cast structural head shown in Figure 18; and

Figure 20 is a top plan view of a cast structural head used on a side column.

In the embodiment of my invention as shown in Figures 1 and 2, 1 represents a concrete column arranged between the floors of a concrete building which are preferably formed in the usual manner by pouring the concrete into a form with the reinforcing rods extending vertically therein and in practice these rods preferably extend above the form to enable the reinforcing rods of the column above to be connected thereto and to allow the structural head to be interlocked therewith as will be more fully hereinafter described. In using a structural head as herein shown, when a column has been poured to the upper end of the form the head is placed on the top of the form or in its proper position so that when the floor slabs are formed, it will be embedded in the column and the adjacent portion of the slab.

The preferred form of structural head is shown in Figures 1 and 2, of structural head 3 consisting of a flat rectangular metal plate 4 provided with a plurality of vertically disposed openings 5, through some of which the reinforcing rods 2 are adapted to pass, the other openings forming means to receive the concrete for interlocking the head within the same.

The reinforcing rods 2 preferably extend upwardly above the floor slab as in general practice into a column 7 above the lower columns, the reinforcing elements being fabricated as the structure is carried upwardly. Surrounding the outer edge of the head 3 is a laterally projecting shelf formed by Z-shaped bars 8 secured to the head by any suitable means such as welding or rivets 9. These Z-shaped bars 8 are secured together at their corners by means of angled irons 10 bolted or riveted to the vertical walls of the Z bars so that a marginal outwardly extending horizontally disposed flange 11 is arranged around the entire circumference of the head in order to form a support within 65 the slab at a point beyond the column.

In practice the lower reinforcing rods 12 of the slabs 6 are preferably bent upwardly over the shelf as indicated at 13 and turned downwardly into the openings 5 of the head. The upper reinforcing rods 15 extend entirely across the structural head into the adjacent slabs on the other side of the column so that the structural head and reinforcing elements of the column and slabs are connected together and in practice these reinforcing elements of the slabs cross each other at right angles as shown.

After the head and reinforcing elements have been placed in proper position on the upper end of the columns, the concrete is poured into the mold in the usual manner and the concrete fills all the openings 5 in the head so as to key the same to the slabs and columns. At the same time the concrete enters the openings around the reinforcing rods 2 of the column and rods 12 of the slabs so that the rods are tightly locked in the head, the Z shaped bars 8 and flanges serving as an additional supporting means and locking means for the slabs in tying the reinforcing elements of the columns and slabs together.

In the embodiment of my invention as shown in Figure 3 I disclose a construction identical with that illustrated in Figures 1 and 2 with the exception that the vertical portions of the Z bar 8' are apertured as shown at 82 through which the lower reinforcing rods of the slabs are adapted to pass as clearly shown, these rods extending under the head into the columns and can be connected together and connected to the upper reinforcing rods 15' of the slabs whereby an additional means of interlocking the reinforcing rods of the slabs and head together is formed, which provides means to withstand the compression in the slab adjacent the head.

From the above description it will be seen that I have provided a structural head of such a construction that the reinforcing rods of the column and the reinforcing rods of the slabs are united through the medium of the head which is of a sufficient size to provide means to support the slabs beyond the columns so as to resist the shearing and flexural stresses which occur adjacent the column.

In the modification of structural head as shown in Figures 4 and 5 instead of forming the head square as shown in Figures 1 and 2, an oblong head 16 is provided having the usual lateral flange and in this instance the Z shaped bar 17 is omitted from one side thereof to allow the head to be used in a side column instead of a central column and in this form the reinforcing rods 18 of the side column pass through the openings 19 formed in the head and the lower reinforcing rods 20 of the slabs are arranged and connected to the head in substantially the same man-

ner as shown in Figure 2. The upper reinforcing rods 21 of the slab have their ends turned downwardly into the openings through which the vertical rods 18 of the column pass so as to tie these rods to the head.

In Figure 6 I show a structural head 22 formed of an apertured plate having the lateral flange omitted from two of its sides as the Z shaped bars 23 are only secured to two of its side edges, which produces a construction of head especially adapted to be used on an outside corner column and it is, of course, understood that the reinforcing elements of the columns and slabs can be connected thereto in the same manner as previously described.

In the form shown in Figures 7 and 8, an octagon shaped head 24 is produced comprising a central apertured plate having all of its eight sides provided with Z shaped bars 25 to produce an annular laterally projecting shelf, the bars being secured to the central plate by bolts or rivets.

In the form shown in Figure 9, a circular head 26 is produced having an annular shelf formed by a ring 27 substantially Z shaped in cross section so as to produce a peripheral shelf which entirely surrounds the circular center which can be used in connection with columns and is of such a size that the flange is embedded within the adjacent portions of the slabs beyond the columns.

In the embodiment of my invention as shown in Figure 10, a structural head 28 is formed in substantially the same manner as shown in Figures 1 and 2 having the marginal flange. In this construction one of the corners is cut away as indicated at 29 adapted to receive the I beams 31 and 32 which are connected to the head by bolts within the cut away portion as clearly shown and this construction of head is especially adapted to be used in connection with an elevator shaft in which the I beams form a part of the structure and the reinforcing rods 33 of the slabs extend over the intersecting rods of the slab and are turned downwardly into the openings of the head, the reinforcing rods passing over the I beams as shown in Figure 12, the lower reinforcing rods being bent downwardly to form a connection therewith so that the heads, I beams, columns and slabs will be interlocked together.

In the embodiment of my invention as shown in Figures 13 and 14 I show a construction of head 34 especially adapted to be used in connection with a chute or the like and it is of oblong form having one of its longer edges provided with a cut-out portion 35 into which extends the I beams 36 and 37 secured thereto by bolts 38. The reinforcing rods 39 of the slabs are looped over the upper faces of the I beams and bent downwardly as shown in Figure 14. Some of

these rods terminate short of the I beam and have their ends extending over the Z bars and are bent downwardly into the openings of the plate of the head as clearly shown.

In all of the constructions of heads as previously described, the unit was formed by a plate of such a size that the marginal shelf carried thereby extended into the adjacent portions of the slabs a sufficient distance to withstand the stresses and while I have shown various forms of heads and manner of forming the same, I am aware that various changes can be made in the shape and sizes of these heads without departing from the spirit of my invention.

In the embodiment of my invention as shown in Figures 15 and 16 I disclose a built up type of head especially adapted to be used in connection with large buildings where thicker slabs are used. In constructing a head of a series of elements as shown, the same is preferably formed of two spaced plates 40 and 41 between which are secured by rivets or any other suitable means as shown at 42 radially extending I beams 43 and 44 which have their outer ends formed with laterally extending lugs 45 and 46 adapted to be riveted to the vertical portion of an L bar 47 herein shown formed of a single piece of metal extending entirely around the outer edge of the head and while I have shown these bars riveted, it is, of course, understood that they could be secured together by any suitable means, such as bolts, rivets or welding. This provides a built-up construction composed of central spaced plates with an annular shelf spaced therefrom. The plates 40 and 41 are provided with aligning square openings 48 to allow the steel frame 49 of the building to pass upwardly therethrough and these plates are also apertured to receive the reinforcing rods of the column surrounding the frame and are adapted to have connected thereto the reinforcing rods of the adjacent portions of the slabs. In this form I provide openings 50 for the vertical reinforcing rods 51 and the reinforcing rods 52 of the slabs have their ends 53 turned downwardly so that they will extend through the aligning openings in the top and bottom plates 40 and 41 of the head as clearly shown in Figure 16 and in practice I preferably provide additional openings in these plates so that the concrete will be keyed thereto.

In the modification shown in Figure 17 I illustrate a structural head for a side column of the built-up type constructed substantially as shown in Figures 15 and 16, a portion of the same being cut away and a transverse beam 54 employed to support the free edges of the plates 55 and the L bar 56. It is, of course, understood that the shape and construction can be changed to meet the

requirements of the building under construction.

In the embodiment of my invention as shown in Figures 18 and 19 I show a structural head 57 of cast metal having an annular shelf formed by a flange at its lower edge, the same being adapted to be used in substantially the same manner as the preferred form and in this construction the hub portion is provided with a central opening to receive a tubular column of the steel structure and also has a lateral flange 59 provided with a plurality of openings adapted to receive the vertical reinforcing rods of the column and horizontally disposed rods of the slabs.

In Figure 20 I have shown a cast construction partly cut away, especially adapted to be used in connection with side columns, the construction being substantially the same as shown in Figures 18 and 19 in order to provide means for interlocking the various reinforcing rods of the columns and slabs together and for keying the head in position within the slabs and columns.

While in the specification and drawing I have described various forms of structural heads to be used in connection with concrete constructions, I am aware that the various shapes can be modified to suit the particular construction of building being formed and therefore I do not wish to limit myself to any particular shape of structural head as my invention consists of a structural head of sufficient size to extend outwardly beyond the column and having a lateral flange embedded within the adjacent slabs.

The important function accomplished by my improved construction of structural head is the effective resistance of the severe shearing and flexural stresses which occur in the slab where the same joins the column by supplying an effective and adequate support for the slab out far enough from the column where the slab is in itself strong enough to resist safely the shearing and flexural stresses that come upon it. In connection with the reinforcing rods of a column and slabs, I provide better conditions for resisting shear in the slab just outside of the head and by having the slab rods pass through the head into the column, the lower part of the slab just outside of the head is reinforced against compression caused by the flexure and a better condition is provided for resisting shear at this point.

From the foregoing description it will be seen that I have provided a structural head or member which when embedded in a column and slab at their junction, will perform the structural functions heretofore performed by the flaring concrete head or capital without increasing the thickness of the slab over what it would be if the flaring concrete head or capital was used, whereby I am able to

produce an all-flat ceiling clear up to the junction of the slab with the column, which is a condition greatly to be desired from an architectural standpoint, as the interior appearance is greatly improved.

What I claim is:

1. In reenforced concrete construction, the combination of concrete columns and a concrete floor supported thereby, of rigid head members having an area greater than the cross sectional area of the columns and embedded in the columns and floor at the junction thereof and a laterally projecting shelf formed on the outer edge of said head.

2. In a reenforced concrete construction, the combination of concrete columns and a concrete floor supported thereby, of flat rigid head members embedded in the columns and extending into the adjacent portion of the floor having a horizontally disposed extension at its lower edge, said heads being provided with openings and reinforcing rods embedded in the columns and floor and passing through said openings for strengthening the structure.

3. A structural head comprising a rigid body portion adapted to be embedded in the column and slabs at the junction thereof, having openings through which the reinforcing rods of the column and slab may pass for tying them thereto and an outwardly extending flange carried by the outer edge of the body portion for forming additional support for the slabs.

4. A structural head, comprising an approximately flat, horizontally disposed rigid body portion of an area greater than the cross sectional area of the column and having openings to receive the reinforcing rods of the column and slabs and an outwardly extending ledge surrounding the outer edge of the body portion and forming additional support for the slabs.

5. A structural head, comprising a rigid body portion having openings through which the reinforcing rods of the column and slab may pass and a flange carried by the outer edge of the body portion at its lower edge.

6. The combination with concrete slabs with directly supporting columns therefor, rigid heads consisting of single pieces of steel plate with an outwardly protruding shelf around the outside, said shelf being set near the bottom of the slab embedded in the columns and extending into the adjacent slabs supported directly thereby and reinforcing means in said slabs passing through and over said heads for strengthening the slab to resist the shearing and flexural stresses that come upon it and reinforcing means in said columns passing through said head for strengthening the column to resist the compression and flexural stresses that come upon it.

7. The combination with concrete slabs

with directly supporting columns therefor, horizontally disposed rigid heads, each consisting of a single piece of steel plate with an outwardly protruding shelf around the outside, said shelf being set near the bottom of the slab, embedded in columns and slabs at the junction thereof, said heads being provided with a plurality of openings and providing room between the top of the head and the top of the slab for several layers of reinforcing rods to pass through in different directions, and reinforcing rods embedded in said columns and slabs and passing through said openings in both horizontal and vertical directions for effectively strengthening the slab just outside the head to resist the shearing and flexural stresses that come upon it there and for effectively strengthening the column to resist compression and flexural stresses.

8. The combination with concrete slabs and directly supporting columns, rigid head members consisting each of a single steel plate having lateral flanges embedded in the slabs and columns at the junction thereof and reinforcing rods embedded in columns and slabs having a connection with said heads.

9. In a reinforced concrete construction, the combination of concrete columns and concrete floor slabs supported thereby, of flat rigid head members consisting of a single piece of metal having angular members secured to their edges embedded in the columns and extended into the adjacent portions of the concrete floor slab, said head being provided with openings, reinforcing rods embedded in the columns and passing through the openings of said head members and reinforcing rods embedded in the slabs and passing horizontally over said heads in two or more directions for strengthening the structure by resisting the stresses that occur in the slab and column caused by the load.

In testimony whereof I hereunto affix my signature.

EDWARD W. HYDE, JR.
